J. G. MUELLER

RAIL BRACE

Filed Feb. 12, 1926

FIG. 1.

FIG. 2. FIG. 3.

FIG. 4.

JOHN G. MUELLER,
Inventor

By Paulmueller
Attorneys

UNITED STATES PATENT OFFICE.

JOHN G. MUELLER, OF DAYTON, OHIO.

RAIL BRACE.

Application filed February 12, 1926. Serial No. 87,910.

This invention relates to insulating devices for rail braces and the like.

The object of the invention is to provide a simple, inexpensive and highly efficient device for preventing the transmission of electric current from one rail to the other of a railroad track through the medium of rail braces or other connecting devices, characterized in that it may be applied to rails of different dimensions with equally satisfactory results. The present invention is an improvement on the insulating device shown and described in Patent No. 1,121,939, issued to me December 22, 1914.

With the insulating device shown in said patent it was necessary to know the size of the rail to which it was desired to apply the insulating device, whereas my present invention may be applied to rails of different dimensions. This universal adaptability of the present insulating device to rails varying from, say, 40 pounds to 136 pounds results not only in economy in manufacture but greatly facilitates the filling of orders as it eliminates the necessity of knowing the size of the rail with which the device is to be used.

In the accompanying drawings:

Figure 1 is a sectional view taken transversely of the rails of a railroad track and longitudinally of a rail brace connecting the two rails equipped with my insulating device.

Figure 2 is a sectional view showing my preferred form of insulating device.

Figure 3 is a sectional view showing a modified form of insulating device.

Figure 4 is a sectional view showing another modified form of insulating device.

In these drawings I have illustrated several embodiments of my invention and have shown the same in connection with a rail brace of a well-known construction, but it will be understood that the invention is not limited in its use to this particular rail brace, or, in fact, to railroad rails, but may be used in connection with rails and connecting devices of various kinds. In the embodiment of the invention here illustrated, the rail brace comprises two rail engaging devices each of which consists of two clamping mem-

bers, an outer clamping member 1 and an inner clamping member 2. These clamping members are constructed and arranged to engage the opposite flanges of the respective rails, and each clamping member is provided at a point beneath the base of the rail with a portion having an aperture 3 extending transversely to the rail. A connecting rod 4 extends through the apertures 3 of the rail engaging device and is provided at its outer ends with fastening devices, such as nuts 5, adapted to draw the clamping members into firm engagement with the flanges of the rails. A spacing member, such as a sleeve 6, is arranged along the intermediate portion of the rod 4 and serves to space the inner clamping members 2 a proper distance apart and to hold them in engagement with the inner flanges of the rails. If desired, nuts 7 may be carried by the rod 4 at the ends of the spacing member 6 to insure the firm engagement of the clamping members 2 with the inner flanges of the rails.

In order to properly insulate the rod 4 from the rails and thus prevent the same from transmitting electric current from one rail to the other, I have provided an insulating device which may be interposed between each of the rail engaging devices 1 and 2 and the connecting rod 4, such insulating device being adjustable to varying sizes of rails, thereby avoiding the necessity of carrying in stock a different size of insulating device for each different size of rail and further enabling orders to be readily filled without being advised of the size of the rail to which the insulating device is to be applied.

To this end I have provided an insulating device comprising a sleeve 8 having sliding members or extensions 9 at each end adapted to be moved relative to said sleeve to lengthen the insulating device to fit the particular rail to which it is to be applied. The sleeve 8 is placed about that portion of the rod 4 which extends through the openings 3 in the rail engaging devices and extends beyond the outer edges 1^a and 2^a of the clamping members 1 and 2 a distance equal to the length of the extension members 9. Thus it will be seen that when the

insulating device is applied to a small sized rail, the inner faces of the extension members 9 will form shoulders which abut against the adjacent ends of the rail engaging devices and the outer faces of said members 9 will be flush with the outer ends of the sleeve 8, as shown in Figure 1, while when the insulating device is applied to rails of larger diameter the outer faces of the sleeves of the members 9 will extend beyond the ends of the sleeve 8, as shown in Figure 2. The sleeve 8 is of such thickness as to fit snugly in the space between the walls of the openings 3 and the rod 4, thereby producing a close fit but permitting the device to be readily assembled. If desired, steel washers 10 may be interposed between the nuts 5 and 7 and the insulating members to prevent undue wear upon the latter.

20 In Figure 3 I have illustrated another form of my universal insulating device comprising a sleeve 11 having sliding members or extensions 12, the extensions 12 terminating in enlarged portions 13 forming shoulders 14 which engage the surfaces 1^a and 2^a of the clamping members 1 and 2.

In Figure 4 I have illustrated still another form of insulating device adapted to be readily adjusted to rails of various sizes. 30 In this form there are two telescoping members or sleeves, one of which has a uniform interior diameter throughout its length while the exterior diameter of its inner portion 15 is smaller than the exterior diameter of its intermediate portion 16 thereby forming a shoulder 17 and the exterior diameter of its outer portion 18 is larger than the exterior diameter of the intermediate portion 16, thus forming a shoulder 19 adapted to engage the surfaces 2^a of the clamping members 2. The other telescoping member comprises a portion 20 terminating in an enlarged portion 21 forming a shoulder 22 adapted to engage the surfaces 1^a of the clamping members 1. The interior diameter of the member 20 is slightly greater than the exterior diameter of the member 15 to provide for the telescoping of said members, whereby this form of insulating device may be readily collapsed or extended to adapt it to different sizes of rails.

The insulating material to be employed is preferably such as to permit of fine and accurate fittings or clearances between the telescoping members and is of such nature as to be practically heat, cold and moisture proof, besides being an acceptable non-conductor of electricity. It also possesses great strength and is practically indestructible. 50 Hardwood fiber has been found to provide a satisfactory insulating material.

It will thus be seen that I have provided an insulating device which will not only prevent the transmission of electric current from one rail to the other of a railroad track

through the medium of rail braces or other connecting devices, but will be adaptable to rails of varying sizes without making any changes therein. This universal adaptation of my improved insulating device results in 70 economy in manufacture, it being unnecessary to carry a plurality of sleeves of different lengths as heretofore. Another advantage is that no delay is entailed in filling orders because my improved device eliminates 75 the necessity of having the size of rails to which it is to be applied. In addition to the above the invention benefits the user because he is relieved of having on hand a variety of sizes of the insulating device. 80

It will be understood that I desire to comprehend within my invention such modifications as may be necessary to adapt it to varying conditions and uses.

Having thus fully described my invention, what I claim as new and desire to secure by Letters Patent, is:

1. The combination with clamping devices adapted to engage the flanges on opposite sides of a rail and having apertures arranged beneath said rail, a rod extending through the apertures in said clamping devices and adapted to hold the same in clamping engagement with said flanges, of an insulating device comprising extensible members adapted to be adjusted to rails of different dimensions.

2. The combination with clamping devices adapted to engage the flanges on opposite sides of a rail and having apertures arranged beneath said rail, a rod extending through the apertures in said clamping devices and adapted to hold the same in clamping engagement with said flanges, of an insulating device comprising a sleeve, and members adjustable on said sleeve to engage clamping devices of different dimensions, whereby the insulating device may be used in connection with varying sizes of rails.

3. The combination with clamping devices adapted to engage the flanges on opposite sides of a rail and having apertures arranged beneath said rail, a rod extending through the apertures in said clamping devices and adapted to hold the same in clamping engagement with said flanges, of an insulating sleeve surrounding said rod for a portion of its length adjacent said clamping devices, insulating extensions on said sleeve, and means for securing said sleeve and extensions in position adjacent said clamping devices.

4. An insulating device of the character described comprising a sleeve and members mounted thereon for increasing the length of said sleeve.

5. An insulating device of the character described comprising a sleeve and one piece members adapted to be slidably mounted on said sleeve to extend the length thereof, each

of said members terminating in an enlarged portion at one end.

6. An insulating device of the character described comprising telescoping members each having a portion whose exterior diameter is greater than the exterior diameter of ¹⁰ the remainder of said members to form shoulders.

5 each member having an enlarged portion at one end.

7. An insulating device of the character

described comprising telescoping members each having a portion whose exterior diameter is greater than the exterior diameter of ¹⁰ the remainder of said members to form shoulders.

In testimony whereof, I affix my signature.

JOHN G. MUELLER.
